BEDRAIL PIN

Edward J. Wilcox, Lakewood, N. Y.

Application May 24, 1945, Serial No. 595,643

1 Claim. (Cl. 85—10)

1

This invention relates to bed rail pins for mounting in bed posts and for securing the rail hooks in the rails.

An object of this invention is to provide a pin of this type which includes a smooth shank and a fluted or ribbed head which is adapted to be embedded in the wooden post or rail.

Another object of this invention is to provide a pin of this type which can be driven or otherwise forced into a hole formed in the wood, the pin having a fluted or ribbed head which will cut its way through the hole and will firmly hold the pin across the hook slot.

A further object of this invention is to provide a pin of this type wherein the flutings or ribs on the head may be either straight or spiral, and the head being adapted to be positioned flush with the outer end of the hole.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail side elevation of a pin constructed according to an embodiment of this invention mounted in a bed post, the latter being shown in section.

Figure 2 is a transverse sectional view through the head of the pin.

Figure 3 is a detail side elevation of a modified form of this invention.

Figure 4 is an inner end elevation of the pin shown in Figure 3, and

Figure 5 is a detail side elevation of another modification of this invention.

Referring to the drawings, the numeral 10 designated generally a bed post or rail which is formed with a slot 11 within which the rail supporting hook is adapted to engage. A pin generally designated as 12 is extended through an opening 13 which is formed in the post 10 and the pin 12 extends across the slot 11. The pin 12 includes a shank 14 which is formed with a bevelled inner end 15. A securing head 16 is carried by the outer end of the shank 14 and is formed of a plurality of spirally arranged flutings or threads 17. The opening 13 is preferably of a size to receive the shank 14 substantially friction tight and when the head 16 is moved inwardly of the opening 13, the pin will rotate and

2

the threads or flutings 17 will cut their way into the wall of the opening and thereby firmly hold the pin in a horizontal position with the shank thereof intersecting the slot 11.

5 In Figures 3 and 4, there is disclosed a modified form of this invention including a pin 12^a having a smooth shank 14^a which is bevelled as at 15^a at the inner end thereof. A head 16^a is carried by the outer end of the shank 14^a and is formed with a plurality of flutings 17^a. In the present instance the flutings 17^a are parallel with the length of the shank 14^a.

Referring now to Figure 5 there is disclosed another modification of this invention embodying a pin 12^b, which has a tapered shank 14^b. The shank 14^b has the larger end thereof innermost and the inner end of the shank 14^b is a bevelled as at 15^b. The shank 14^b has formed integral therewith a fluted head 16^b embodying 10 a plurality of straight flutings 17^b which are parallel with the longitudinal axis of the shank 14^b.

20 In the use of this pin the pin has a length sufficient to provide for the shank 14 extending across the slot 11 and the outer end of the head 16 is adapted to be flush with the adjacent side of the post 10. The hole 13 is drilled through one side of the post 10 and communicates with the slot 11. The shank 14 is then moved into the 25 opening 13, the bevelled end 15 facilitating the positioning and movement of the pin shank through the opening. As the spiral head 16 engages in the opening 13 the pin will partially rotate, the flutings 17 cutting their own threads 30 into the wall of the opening and thereby firmly and tightly holding the pin with the shank 35 thereof intersecting the slot 11.

Where a pin as shown in Figures 3 or 5 is used, the pin is inserted in the same manner but in 40 these instances the pin does not rotate as it is forced into the opening. The pin may be inserted into the opening 13 by any suitable means which will provide sufficient pressure to force the pin through the opening.

45 What I claim is:

A bed rail pin comprising a solid shank member having a smooth surface, a fluted head at one end of said shank, said shank being of a longitudinally tapered configuration converging at the adjacent end of said head, the root diameter of said fluted head being substantially equal to the diameter of the convergent end of said shank, and a bevelled edge on the opposite enlarged end of said shank.

EDWARD J. WILCOX.
